Des. 185,456
Patented June 9, 1959

185,456

COMBINED BOTTLE AND SUPPORTING SLEEVE

John C. Michalek, Lake Villa, and Michael A. Grayson,
Waukegan, Ill., assignors to Abbott Laboratories, North
Chicago, Ill., a corporation of Illinois

Application January 15, 1958, Serial No. 49,264

Term of patent 14 years

(Cl. D58—26)

FIG. 1

FIG. 2

Figure 2 is a view of one side thereof, the other side being substantially the same;

The essential features of our design reside in the portions shown in full lines.

We claim:

The ornamental design for a combined bottle and supporting sleeve, substantially as shown and described.
